CHILD'S SLEEPING BAG

Elizabeth D. Mathews, San Francisco, Calif.

Application July 26, 1954, Serial No. 31,605

Term of patent 14 years

(Cl. D92—2)

Fig. 1.

Fig. 2.

Fig. 3.

Fig. 4.

Fig. 1 is a front elevational view of a child's sleeping bag showing my new design.

Fig. 2 is a rear elevational view thereof.

Fig. 3 is a sectional view thereof taken along the line 3-3 in Fig. 1.

Fig. 4 is a sectional view thereof taken along the line 4-4 in Fig. 1.

I claim:

The ornamental design for a child's sleeping bag, substantially as shown.
